SHIM CLIP OR THE LIKE FOR ADJUSTABLY MOUNTING A SHORE SUPPORT ON A COLUMN OR A WALL

Dole J. Kelley, Jr., Jacksonville, Fla., assignor to Strickland Systems, Inc., Jacksonville, Fla.

Filed May 2, 1974, Ser. No. 466,215

Term of patent 14 years

Int. Cl. D8—08

U.S. Cl. D8—246

FIG. 2

FIG. 1

FIG. 3

FIG. 4

FIG. 5

FIG. 6

FIG. 7

FIG. 1 is a front isometric view of the shim clip or the like for adjustably mounting a shore support on a column or a wall showing my new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top side elevational view thereof; and

FIG. 7 is a bottom side elevational view thereof.

I claim:

The ornamental design for a shim clip or the like for adjustably mounting a shore support on a column or a wall, substantially as shown and described.
